UNITED STATES PATENT OFFICE.

MORRIS KALLENBACH, OF BOODY, ILLINOIS.

WAGON ELEVATOR AND DUMP.

SPECIFICATION forming part of Letters Patent No. 366,399, dated July 12, 1887.

Application filed February 18, 1887. Serial No. 228,104. (No model.)

To all whom it may concern:

Be it known that I, MORRIS KALLENBACH, of the town of Boody, county of Macon, and State of Illinois, have invented a certain new 5 and useful Elevator and Dump, of which the following is a specification.

My device, while applicable to a variety of uses, is especially designed for cribbing corn; and the novelty consists in certain details of 10 construction and combinations of parts, as hereinafter set forth and claimed.

In the drawings accompanying and forming a part of this specification, Figure 1 is a side view of my device with a wagon on the foot 15 of the elevator. Fig. 2 is a section of the dump-track on broken line *x*, Fig. 1. Fig. 3 is a section of the elevator-track on broken line *y*, Fig. 1. Fig. 4 is a side elevation of my device with a wagon on the dump. Fig. 5 is 20 an enlarged perspective view of the pulley that connects with the wagon. Fig. 6 represents a runner that is used in moving the device sidewise along a crib, or from one crib to another; and Fig. 7 is a longitudinal vertical 25 section of a dump-rail.

The elevator-track consists of two parallel inclined rails, *a*, composed each of a tread-rail, *a'*, and flanges *a''*.

The dump is formed of two parallel rails, *b*, 30 pivotally supported and ordinarily resting in alignment with the rails of the elevator-track. Each rail *b* is composed of a tread-rail, *b'*, and flanges *b''*, projecting both above and below the tread-rail. The tread-rails of the dump-track do not reach the upper end of the dump, 35 (see Fig. 7,) and an adjustable clamp, *e*, is connected with and extends across the upper end of each rail. Supports *g* provide a pivotal support for the dump. Supports *g'* sustain the elevator-track. Cross-bars *h* and *l* are braces, and *i* *i'* sills for the supporting-frame. Bar *s* connects the dump-rails at their upper ends. Strips *c* extend from *g'* to *g* in line with the lower surface of the elevator-track, and form guides to hold the dump in alignment with the elevator. Arm *f* is pivotally attached to the strips *c* at *m*, and a pulley or pulleys, *o*, are secured to the upper end thereof. Bars *d* terminate the tilt of the 45 dump, as indicated in Fig. 4. A rope, *q*, extends from the pulley *n* on the wagon around

a pulley *o* back to *n*, around another pulley *o*, and down to and around pulley *p*, giving a force at the termination of the rope a three-fold purchase on the wagon. 55

The hooks *n''* in Fig. 5 connect with the tongue-bolt of the wagon on opposite sides of the tongue. The band *n'* fits over the tongue, and the ring *n'''* provides an attachment for the rope. 60

A rope, *r*, connects with the dump below its pivot, and provides means for righting said dump. A hitch-pin, *k*, enables the wagon to be lowered slowly by coiling the rope around the pin. The pivot-pins *v* extend inwardly to 65 an extent sufficient to arrest the upward throw of arm *f*, and said arm rests, ordinarily, on bar *s*. Sill *i* is curved at its ends to form a runner, and by placing runner *t* under sill *i'* the lower end of the elevator-track is raised clear 70 of the ground, and the device is in condition to be moved sidewise on the runners. The upward projections *u* fit against the sides of the sill and prevent lateral displacement of the runner. 75

In operation a loaded wagon is hauled to the foot of the elevator, the doubletree is detached from the tongue, and the pulley *n* connected therewith. The team is driven to the side of the elevator and hitched to rope *q*. The wagon is raised to about the position shown in Fig. 80 1, the front end-gate is removed, and the wagon drawn up the incline until the front wheels are in the slots of the dump, (indicated by *b'''* in Fig. 7.) Then, if there is no restraint on the dump, the wagon will tilt forward; but 85 if the rope *r* is secured to the frame, as indicated in Fig. 1, the wagon will maintain its position after the team is detached, and the dump may be effected in any desired manner by a manipulation of rope *r*. The arm *f* descends with the dump, thus facilitating the operation, and rises with the same to carry its pulleys in proper position to draw the wagon up the incline. 90

A crib is supposed to be in position to receive the corn from the wagon; but it is obvious that a car or other receptacle may take the place of the crib, and that the wagon may contain other commodities than corn, the result in either case being the easy accomplishment by horse-power of that which is usually 95 done by manual labor. 100

I claim as new and desire to secure by Letters Patent—

1. In combination, the inclined elevator-track and the pivotal dump-rails slotted at 5 their upper ends and resting, ordinarily, in alignment with the rails of the elevator-track, as and for the purpose set forth.
2. In combination, the inclined elevator-track, the pivotal dump resting, ordinarily, in 10 line with the elevator-track, the pulley-bearing arm pivoted in the supporting-frame and projected beyond the upper termination of the dump, and the stop-frame to limit the tilt of the dump, as and for the purpose set forth.
- 15 3. In combination, the track *a*, supported by uprights *g'*, the dump-rails *b*, pivotally supported by upright *g* and provided with downwardly-projecting flanges, strips *c*, adapted to the flanges of the dump-rails, clamps *s* on the upper ends of the dump-rails, pulley-bearing 20 arm *f*, pivotally connected with the frame and projected beyond the upper termination of the dump, pulley *p* at the bottom of the frame, pulley *n*, adapted to be connected to a wagon, elevating-rope *q*, stop-frame *d*, and tilting-rope 25 *r*, as and for the purpose set forth.
4. The pulley *n*, band *n'*, hooks *n'' n'''*, and ring *n''''*, all in combination, for the purpose set forth.
5. The pulley *n*, band *n'*, and the hooks *n''* 30 *n''''*, all in combination, for the purpose set forth.

MORRIS KALLENBACH.
